CLAIM

The ornamental design for a food package with bag, as shown and described.

DESCRIPTION

FIG. 1 is a top plan view of a food package with bag showing our new design.

FIG. 2 is a bottom view of the food package with bag of FIG. 1.

FIG. 3 is a left side elevation view of the food package with bag of FIG. 1.

FIG. 4 is a right side elevation view of the food package with bag of FIG. 1.

FIG. 5 is a front elevation view of the food package with bag of FIG. 1.

FIG. 6 is a rear elevation view of the food package with bag of FIG. 1; and,

FIG. 7 is an isometric view of the food package with bag of FIG. 1.

The broken lines shown in FIGS. 1 through 7 depict portions of the food package with bag that form no part of the claimed design.

1 Claim, 7 Drawing Sheets
